UNITED STATES PATENT OFFICE.

WILLIAM KRAFVE, OF FALL RIVER, MASSACHUSETTS, ASSIGNOR TO CAPITOL MOTORS CORPORATION, OF FALL RIVER, MASSACHUSETTS, A CORPORATION OF MASSACHUSETTS.

ENGINE-MOUNTING.

1,314,673.

Specification of Letters Patent. Patented Sept. 2, 1919.

Application filed June 6, 1918, Serial No. 238,418. Renewed July 12, 1919. Serial No. 310,456.

To all whom it may concern:

Be it known that I, WILLIAM KRAFVE, a citizen of the United States, residing at Fall River, in the county of Bristol and State of Massachusetts, have invented a new and useful Improvement in Engine-Mountings, of which the following is a specification.

This invention relates to certain new and useful improvements in an engine mounting 10 and it resides in a flexible mounting embodying a three-point suspension for the power plants or motors of automobiles by which the mounting will be permitted to yield or accommodate itself to the twisting 15 or straining of the chassis frame.

In its simplest form, the invention consists of a pair of trunnion-like suspending members, that extend from the opposite sides of the rear portion of the engine base 20 or crank case, and a central suspending member at the forward portion thereof, which central point of suspension may be the forward extension of the engine crank shaft and which finds bearing in a spanner frame arranged transversely of and secured to the vehicle chassis.

In the drawings, which exemplify one form that the present invention may assume,

Figure 1 is a top plan view of the forward 30 end portion of a motor vehicle showing the invention applied thereto.

Fig. 2 is a transverse section thereof on line 2—2 of Fig. 1, depicting the forward mounting.

Fig. 3 is a similar view on line 3—3 of Fig. 1 illustrating the rear mounting for the motor, and

Fig. 4 is a vertical section on line 4—4 of Fig. 2 further illustrating the forward 40 mounting.

Referring more in detail to the accompanying drawings, the numerals 1 designate the side frame members of the vehicle chassis, which are of the usual channel bar formation and between which the motor 2 is arranged.

A spanner frame or transverse frame member 3 has its ends flanged and bolted or secured in the opposing channels of the side frame member, as at 4. The spanner frame is bowed or depressed between its ends, as depicted in Fig. 2, and is formed in its upper edge with a central bearing or seat 5. A cap or strap bearing 6 is secured to the spanner frame over the bearing 5 by bolts 7

which preferably pass vertically through said frame, the bearing 8 of the strap and bearing 5 being semi-circular and transversely concave to receive a partly spherical bushing 9. The trunnion 10 or engine shaft extension, as the case may be, finds support in this rockable bushing or journal bearing 9.

The rear support for the motor comprises two points of suspension, one on each side 65 of the same. Bolted to the upper face of each side flange 11 of the engine base or crank case is a hanger or bracket 12 in the outer side face of which is threaded a trunnion 13 having a ball or globular end overhanging the adjacent frame member 1. A two-part socket bearing member 14 is bolted to the upper edge of each channeled frame member 1, a packing strip 15 being interposed between the supermost sections of said 75 bearing member to provide a tight and dirt proof joint.

In practice, the caps or upper sections of the socketed bearings 14 are removed as well as cap bearing 6 whereupon the engine or 80 motor may readily and easily be set in place with the trunnion supports engaged in their bearings or seats. The component sections of the three bearings are then bolted over the trunnions for securely holding them in 85 their seats. The motor is thereby firmly supported in a most efficient manner without the employment of a complicated hanger requiring the removal of a large number of bolts and nuts.

The mounting is flexible to accommodate itself to the twisting or relative movement between the frame members of the chassis. In traveling over rough roads especially, the chassis frame is subjected to much strain and 90 torque which often causes a weakening of the frame and a loosening of the engine mounting. Again, the engine mounting becomes loosened through vibration of the motor. These severe conditions are effectively 100 taken care of by this flexible mounting. Furthermore, by removing cap bearing 6 the engine may be tilted or rocked on its trunnions 13, or by removing either or both of the latter the engine may be rocked laterally 105 and vertically on its forward trunnion support. The socketed bearings 14 entirely enclose the balled ends of the trunnions 13 to prevent the entrance of dust therein. The bolts, securing the supports 12 to the flanges 110

11, pass on opposite sides of the trunnion mountings to steady and reinforce such mounting. All the parts are readily accessible through the removal of a small number 5 of bolts.

Having thus described my invention, what I claim as new and desire to secure by Letters Patent is—

In combination with the sides of a chassis, and a motor having a flanged base, a 10 pair of bearing members carried by the respective chassis sides, vertical brackets formed to each seat at their lower ends on the flanged base of the motor, said brackets 15 having vertical lengthwise holes formed

therethrough, trunnions carried by the brackets and arranged in said bearings, and bolts extending through the flange of the motor base and through said holes of the brackets and having their heads engaged 20 with the under face of the flanges of the motor base and having nuts seated on the top ends of the brackets.

In testimony whereof I have signed my name to this specification in the presence of 25 two subscribing witnesses.

WILLIAM KRAFVE.
